(57) **CLAIM**

The ornamental design for a tire for motorcycle, as shown and described.

DESCRIPTION

FIG. 1 is a front perspective view of a tire for motorcycle showing my new design;

FIG. 2 is a front view thereof;

FIG. 3 is a left side view thereof;

FIG. 4 is a rear view thereof;

FIG. 5 is a right side view thereof;

FIG. 6 is a bottom view thereof;

FIG. 7 is a top view thereof; and,

FIG. 8 is a partial enlarged view of FIG. 2.

The dash-dot-dash broken lines in FIGS. 2 and 8 of the drawings are used for demarcation of the enlarged portion of the tire for motorcycle illustrated in FIG. 8. The dash-dot-dash broken lines form no part of the claimed design.
